W. H. BOCK.
NON-REFILLABLE BOTTLE.
APPLICATION FILED MAY 17, 1912.

1,047,732.

Patented Dec. 17, 1912.

UNITED STATES PATENT OFFICE.

WALTER H. BOCK, OF NEW YORK, N. Y., ASSIGNOR OF ONE-HALF TO VICTOR BOCK, OF NEW YORK, N. Y.

NON-REFILLABLE BOTTLE.

1,047,732.

Specification of Letters Patent. Patented Dec. 17, 1912.

Application filed May 17, 1912. Serial No. 697,851.

To all whom it may concern:

Be it known that I, WALTER H. BOCK, a citizen of the United States, and a resident of the city of New York, Corona, borough 5 of Queens, in the county of Queens and State of New York, have invented a new and Improved Non-Refillable Bottle, of which the following is a full, clear, and exact description.

10 This invention relates to improvements in bottle stoppers, and particularly to what are known as non-refillable bottles, and has for an object to provide a structure which will permit the ready flow of fluid from the bottle or other receptacle, and will resist refilling of the bottle.

15 A further object of the invention is to provide an improved structure which may be quickly applied to the neck of the bottle 20 after the bottle has been filled without the use of tools or implements.

25 A still further object of the invention is to provide an improved stopper structure designed to resist refilling of the bottle to 30 which it is connected, formed so as to prevent a tool or other instrument to be inserted sufficiently far to raise the valve structure forming part of the stopper whereby tampering with the stopper will not in 35 any way affect its efficiency unless the stopper is broken to a greater or less extent.

In carrying out the objects of the invention, a stop or partition is provided near the lower end of the neck of the bottle to 35 which the device is connected, and a valve structure or protecting mechanism arranged above the stop. This structure is formed with a freely reciprocating valve member 40 actuated by gravity and also by the flow of liquid in either direction, the flow of liquid in one direction causing the valve to be unseated for allowing the fluid to flow from the bottle, and fluid flowing in the opposite direction causing the valve to be seated against the action of gravity, whereby liquid is prevented from entering the bottle. Arranged between the valve structure and the outer end of the bottle are a plurality of baffling members, partitions, stops, and the like,

which are designed to prevent any tampering 50 with the valve structure.

A practical embodiment of the invention is represented in the accompanying drawings forming a part of this specification, in which similar characters of reference indicate 55 corresponding parts in all the views.

Figure 1 is a longitudinal vertical section through an embodiment of the invention shown applied; Fig. 2 is a view similar to Fig. 1, except that the same is shown substantially inverted; and Fig. 3 is a detail perspective view of the various parts of the stopper structure shown slightly separated.

Referring to the accompanying drawings by numerals, 1 indicates a bottle of any desired kind, having a neck 2. The neck 2 is preferably formed with a beveled opening or bore 3 enlarged at 4, whereby an offset or shoulder 5 is provided. A plurality of sockets 6 are also provided for accommodating spring catches 7 hereinafter fully described. Resting on the shoulder 5 is a resilient packing washer 5' supporting a frusto-conical shaped sleeve 10 provided with a plurality of apertures 11 and an annular flange 12, the annular flange being the part which rests on the washer 5'. This sleeve is designed to receive a conical shaped valve member 13 formed with apertures 14 and an annular flange 15. The conical part of the 80 valve member 13 is adapted to fit against the inner part of the sleeve 10 when the bottle is in an upright position, as shown in Fig. 1, and the annular flange 15 is designed to rest against the upper surface of the 85 flange 12. When the conical shaped valve 13 is in the position shown in Fig. 1, the bottle is of course sealed against the entrance of anything. Resting on the annular flange 12 and encircling the annular flange 15, is 90 a ring 16 which supports at its upper end a radially notched disk 17 formed with a raised annular portion 18 on which is positioned the annular flange 19 of a substantially conical shaped member 20. The member 20 is provided with an aperture 21 arranged centrally thereof and of a size preferably slightly less than the center portion

22 of the disk 17. This will prevent any tool or other implement from being forced past the disk 17 into contact with the valve member 13. The member 24 is provided 5 with a restricted opening 25 which merges into an enlarged opening 26, in which may be forced a cork or other stopper 27. This cork or stopper 27 is designed to be applied in the usual manner. The upper end of the 10 member 24 is provided with a flange 28, beneath which is positioned a resilient washer 29. The washer 29 is designed to be compressed when the member 24 is being arranged in position so as to permit the spring 15 7 to snap into the sockets 6 and thereby lock the member 24 and the remaining parts of the device correctly in position. The washers 5' and 29 being of somewhat resilient material will take up lost motion and cause 20 a substantially tight fit for all the parts, with the exception of course, of the valve member 13 which is permitted a free back and forth movement.

In operation, after the bottle has been 25 filled the structure shown in Fig. 3 is forced into the bore 3 of the neck 2 until it assumes the position shown in Fig. 1. The stopper 27 is then applied and the operation is complete. When it is desired to empty 30 or remove some of the contents from the bottle 1, the bottle is inverted as shown in Fig. 2, which will cause the valve member 13 to move down by gravity to substantially the position shown in Fig. 2 assisted by the 35 pressure of the fluid. This will of course allow the fluid to pass through the apertures 11 and 14 and also through the slots in the plate 17 and the aperture 21 in member 20. The fluid from the bottle is permitted 40 to flow freely as long as the bottle is inverted but upon moving the bottle to substantially an upright position, the valve member 13 will reseat itself automatically. In case it should be attempted to force fluid 45 into the bottle 1 the valve member 13 will reseat itself by gravity, or if the bottle is inverted will reseat itself by the pressure of the fluid acting in the chamber 30 so that the fluid will not be able to pass through the 50 sleeve 10. In constructing the various parts of the device the same may be made of any desired material but preferably the parts, except the washers, are made from metal and aluminum is found to be very desirable. As is well known, aluminum is 55 comparatively light so that if the valve member 13 for instance was made of aluminum, the same would not float but would be easily actuated by any fluid attempting to pass 60 into the bottle 1.

Having thus described my invention I claim as new and desire to secure by Letters Patent:—

1. In a device of the character described,

the combination with a bottle formed with a 65 neck having a bore extending therethrough, of a valve structure arranged in said bore, said valve structure being formed with a frusto-conical shaped seat having a plurality of substantially radiating apertures, and a 70 cone normally fitting said seat with one end projecting from the open end thereof, said cone being formed with an annular flange resting on the upper end of said seat when the cone is in a closed position, and with a 75 plurality of radiating apertures for permitting the flow of fluid from one side of the cone to the other when the cone is unseated, guiding means engaging the flange on said cone for guiding the cone in its movement, a 80 guarding member arranged above said guiding means, and means for holding the guarding member, guiding means, and valve structure in position.

2. In a device of the character described, 85 the combination with a bottle formed with a neck having a bore therein provided with an annular shoulder, of a frusto-conical shaped sleeve formed with an annular flange and a plurality of apertures, said annular flange 90 being positioned over said shoulder and adapted to be supported thereby, a conical shaped valve member fitting into said sleeve and normally closing said apertures in the open end of the sleeve, guiding means for 95 guiding said valve member, and means arranged above said guiding means for protecting said valve member.

3. In a device of the character described, 100 the combination with a bottle formed with a neck having a bore extending therethrough, of a valve structure arranged in said bore, said valve structure being formed with a frusto-conical shaped seat having a plurality of substantially radiating apertures, and a 105 cone normally fitting said seat with one end projecting through the open end thereof, said cone being formed with a plurality of radiating apertures arranged in a different plane from the apertures in said seat 11 when said cone is resting on the seat, said apertures being designed to permit the flow of fluid from one side of the cone to the other when the cone is unseated, and guiding means arranged above said valve structure.

4. In a device of the character described, 120 the combination with a bottle formed with a neck having a bore extending therethrough, of a valve structure arranged in said bore, said valve structure comprising a frusto-conical shaped seat having a plurality of apertures in the side walls thereof, and a cone having apertures in the side walls thereof fitting said seat, one end projecting from 125 the open end thereof, the apertures in said seat and in said cone being arranged in a different plane when the cone is resting on

said seat, said cone being formed with an annular flange overlapping the upper edge of said seat, a guiding ring surrounding said flange for guiding the flange and cone in a reciprocal motion, and means for protecting and holding in position said guiding ring, said cone, and said seat.

In testimony whereof I have signed my name to this specification in the presence of two subscribing witnesses.

WALTER H. BOCK.
